United States Patent Office.

ANTHONY HILTS, JR., OF SPRINGDALE, OHIO.

Letters Patent No. 69,842, dated October 1, 1867.

IMPROVEMENT IN HARVESTERS.

The Schedule referred to in these Letters Patent and making part of the same.

TO ALL WHOM IT MAY CONCERN:

Be it known that I, ANTHONY HILTS, Jr., of Springdale, county of Hamilton, and State of Ohio, have invented certain new and useful Improvements in Tongues for Reapers; and I hereby declare that the following is a true, exact, and full description of the same, reference being had to the accompanying drawings, and to the letters of reference marked thereon. In the annexed drawings, which make a part of this specification—

Figure 1 represents the frame of a reaping machine with the tongue attachment.

Figure 2 is a plan view of the attachment.

The letter A represents the pole or tongue. C is a metal plate of suitable width and thickness, with a radial arm, b, extending from it, the end of which is bolted to the tongue. The plate C is quadrantal in form, and is cut out of the same plate of metal with the radial arm b. The inner end of C is also bolted to the tongue, with the convex edge placed outward. The under side of the tongue is furnished with a device corresponding exactly in form with plate C and radial arm b, and held in position with the same bolts that confine C and b to the tongue A. E designates a bar, the inner end of which is bolted to the reaping machine, as seen in fig. 1. Against the outer side of bar E is made to rest the tongue A, which has an inward play on a pivot that passes through it and through the metal plates m, one plate C resting on the tongue and on bar E at top, and the other at bottom. The whiffle-tree H is confined to the tongue with the same bolt that attaches the plates m to tongue A. On the surface of the plate C that rests on the top of tongue A is fastened the stop S, against which the whiffle-tree rests at one end, when it is desired to turn the reaping machine to the right. The plates C have corresponding perforations to receive a bolt, which, when in position, will arrest the motion of tongue A to the right at any angle the operator may require.

The advantage I claim for my tongue-attachment is the increase of leverage by operating it in advance of the reaper, and thus saving both time and power in harvesting a field of grain.

Having thus described my invention, what I claim, and desire to secure by Letters Patent, is—

The quadrantal plate C, when provided with stop S and perforations i i, in combination with bar E and tongue A, all operating in the manner and for the purpose described.

In testimony whereof I set my signature in presence of two witnesses.

ANTHONY HILTS, Jr.
